UNITED STATES PATENT OFFICE.

JOSEPH K. BURGESS, OF BLUEFIELD, WEST VIRGINIA.

GARMENT-RETAINER.

1,257,800.

Specification of Letters Patent. Patented Feb. 26, 1918.

Application filed February 7, 1913. Serial No. 746,757.

To all whom it may concern:

Be it known that I, JOSEPH K. BURGESS, a citizen of the United States, residing at Bluefield, in the county of Mercer and State 5 of West Virginia, have invented certain new and useful Improvements in Garment-Retainers, of which the following is a specification, reference being had therein to the accompanying drawing.

10 This invention relates to garment retainers and is particularly designed for men's use for retaining the outer shirt in proper position within the trousers.

It is a matter of common experience that 15 a man's outer shirt has a tendency to ride out of his trousers, especially when suspenders are not worn, and it is the object of this invention to effectively check this tendency, at the same time providing for the purpose a 20 device which is comfortable, simple in construction, inexpensive to manufacture and entirely hidden from view when worn. A further object is to provide an improved clasp which may be readily engaged with 25 and disengaged from the shirt, and which will firmly grip the garment without danger of slipping or injuring the same.

The invention will first be hereinafter described in connection with the accompanying 30 drawings, which constitute a part of this specification, and then more particularly pointed out in the claims at the end of the description.

In the drawings:

35 Figure 1 is a front elevation of a device embodying this invention, the same being arranged substantially in the position it occupies when in use;

Fig. 2 is a top plan view of the device;

40 Fig. 3 is an enlarged front elevation of one of the clasps engaged with a fold of a garment or shirt;

Fig. 4 is a sectional view taken on the line 3-3 of Fig. 3; and

45 Fig. 5 is a detailed upper end view of one of the clamps alone, its members being interlocked.

The retaining device illustrated in these drawings as one form of the invention, comprises two straps A, A', of elastic or other suitable material, arranged transversely to each other and equipped at or near their ends with clasps B adapted to engage the shirt or other garment to be retained in 55 place. One of the straps, A for instance, may be provided with an auxiliary strap α

having its ends secured by stitching or other suitable means, as at α' , thus forming a loop through which the other strap A' is passed and in which the latter has free movement 60 both longitudinally and laterally for automatically adjusting the device to the movements of the body of the wearer.

Adjacent end portions of the straps may be connected together by side bands C, C, 65 which with said straps form two loops D, D, Fig. 2, through which the legs of the wearer are inserted when the device is put on. The rear ends of said bands may be permanently 70 secured to the rear end portions of the straps A, A', as at c, while the front ends of said bands are preferably provided with swivel connections c' with the front ends of said straps in order to more fully adapt the device to freely follow the movements of the 75 body. These swivel connections may be separable for convenience in putting on the retainer and they are placed on the outside of pads c² on the front ends of the bands so as to leave the inner surfaces of said bands 80 smooth where they bear against the body, thus insuring comfort to the wearer. The front ends of the straps may be adjustably attached to said swivel connections by means of sliding buckles E, Fig. 1, so that the size 85 of the device may be readily altered to fit the wearer. The front clasps B are preferably fastened to the pads c² instead of directly to the straps.

The retainer may also be put on by separating the swivel connections c' thus detaching the front ends of the straps from the pads c². The free ends of said straps may then be passed through the crotch and connected again to the pads in proper position, 95 thereby avoiding the necessity of inserting the legs through the loops D, D, if desired.

Each of the clasps B may consist of a loop member b and a stud member b' flexibly connected to the device independently of each other, whereby one member may be moved with respect to the other for interlocking them and clamping a portion of the garment between them. The side bars of the loop member converge toward the free end thereof, while the stud portion may have a generally rectangular body portion b² and a restricted or narrowed free end portion b³ terminating in an offset head or button b⁴. Instead of this free end portion of the stud 110 member being made of a continuous piece of wire, as heretofore in similar devices, the

wire is severed at the end of said member, thus splitting the head or button in half and providing two resilient parts which are capable of springing laterally apart or giving 5 inwardly toward each other as may be required for firmly gripping the garment without danger of tearing the same.

In order to employ the retainer for the purpose designed, it is put on over the underwear by inserting the legs through the loops D, D and drawing the device up snugly under the crotch, the bands C, C being arranged about the hips. The clasps are then engaged with folds of the shirt F, as shown 10 in Figs. 3 and 4. The crossed straps which pass under the crotch limit the upward movement of the device and thus prevent the shirt from riding up. When the trousers are put on over the device, they entirely 15 cover and conceal the latter, so that the wearer's appearance is not marred at all but rather improved by reason of the fact that the shirt is always retained with just the proper fullness above the trousers.

20 Having thus described my invention, what I claim as new and desire to secure by Letters Patent of the United States, is:

1. A garment retainer having two straps crossed upon one another at their centers 25 and adapted to be passed under the crotch, bands connecting the adjacent front and rear portions of the respective straps and adapted to be arranged about the hips, the connection between the bands and the rear portion of 30 the straps being intermediate the ends of said straps, pads on said bands at the front ends thereof, connections between the front end of said straps and the pads at a point below the position of attachment of the retainer to a garment, and means for attaching 35 the retainer to a garment, certain of the attaching means being carried by the pads and others by the rear ends of the straps.

2. A garment retainer having two straps 40 crossed upon one another at their centers and adapted to be passed under the crotch, bands connecting adjacent front and rear portions of the respective straps and adapt-

ed to be arranged about the hips, the connection between the bands and the rear portions of the straps being a substantial distance 45 from the rear ends of said straps, pads on said bands, detachable swivel connections between the straps and said pads, one part of said swivel connection being carried at 50 the end of said straps and the other part upon the outer face of the pads, and means for attaching the retainer to a garment, certain of said attaching means being carried by said pads.

3. A garment retainer having two straps crossed upon one another at their centers and adapted to be passed under the crotch, bands connecting adjacent front and rear portions of the respective straps and adapted 55 to be arranged about the hips, said bands formed of a continuous piece extending from the rear portions of the straps at a point intermediate the ends of said straps and having at their front ends means for attaching 60 said bands to a garment, means upon the rear ends of said straps for attaching the same to the garment, and means for detachably connecting the front ends of the straps 65 to the free ends of the bands at a point below 70 the front garment attaching means.

4. A garment retainer having two straps crossed upon one another at their centers and adapted to be passed under the crotch, bands connecting the adjacent front and 75 rear portions of the respective straps and adapted to be arranged about the hips, the connection between the bands and the rear portion of the straps being intermediate the ends of said straps, detachable connections 80 between the front ends of said straps and the free ends of the bands at a point below 85 the position of attachment of the retainer to a garment, and means for attaching the retainer to a garment.

In testimony whereof I have affixed my signature in presence of two witnesses.

JOSEPH K. BURGESS.
